UNITED STATES PATENT OFFICE.

CLAUDE M. GARLAND, OF CHICAGO, ILLINOIS.

APPARATUS FOR DEVOLATILIZING COAL, WOOD, SHALES, &c.

1,391,825.

Specification of Letters Patent. Patented Sept. 27, 1921.

Application filed March 3, 1919. Serial No. 280,294.

To all whom it may concern:

Be it known that I, CLAUDE M. GARLAND, a citizen of the United States, residing in Chicago, in the county of Cook and State of Illinois, have invented new and useful Improvements in Apparatus for Devolatilizing Coal, Wood, Shales, &c., of which the following is a specification.

My invention has for its object the provision of improved means for coking bituminous coal and devolatilizing such fuels as wood, lignite and shales, whereby the time required for devolatilizing is greatly reduced, the products resulting therefrom increased in quantity and the labor required in the operation greatly lessened.

Further objects and advantages of the invention will be set forth in the description that follows.

The apparatus is intended for the coking of fuels at a low temperature. In this process it has been found that in order to coke such fuels rapidly the fuel must be divided into thin layers in order for the heat to reach the center of the mass. The temperatures used do not as a rule exceed 1200° F.

In my apparatus the coking or devolatilizing is carried out in a cast iron retort which is divided into a number of narrow compartments formed by partitions which extend crosswise of the retort. A large number of these partitions are formed in one retort and a common cover is used for all of the compartments formed by the partitions.

The accompanying drawings which form a part of this specification illustrate more fully my invention. Referring to the drawings in which like numerals designate like parts in the various figures, Figure 1 shows an elevation in section taken on the line XX of Fig. 2. Fig. 2 is an elevation in section taken on the line ZZ of Fig. 3. Fig. 3 is a plan in part section taken on the line YY of Fig. 1. Fig. 4, a detail showing the means of supporting the swinging bottom 12, by the dog 14.

Referring to the drawings the numeral 1 indicates a closed heating chamber which is covered with an insulating medium 20. This heating chamber is supported on the beams 19 at a suitable distance from the ground. Extending through the heating chamber are a plurality of retorts 2 which are preferably made from cast iron. These retorts are divided into a large number of compartments

4, by the cast iron partitions 3. The retorts 2 may be made of any convenient length, preferably not exceeding twelve feet. The width of the retort is approximately 12 inches, while the depth of the retort is approximately 12 ft. The partitions are spaced approximately 4 in. apart and these partitions are made thicker at the top than at the bottom. The sides of the retorts 2 are a little farther apart at the bottom than at the top. The compartments 4 therefore have a tapering section which makes the devolatilized fuel drop out when the swinging door 12 is dropped. The swinging door or bottom 12 is hinged at 13. The lower end of the retort 2 is enlarged to accommodate the swinging bottom 12 so that when the bottom is dropped the fuel slides out without interfering with the bottom. 14 is a dog which normally holds the bottom 12 in the position shown on the drawings. When this dog is moved to one side the bottom drops. Fig. 4 shows a detail of the arrangement of the dog 14. This is pivoted at 24 to the side of the retort 2.

The retorts 2 are closed at the top by the covers 6. The sides of these covers dip into a channel 8 which is cast around the top of the retort. This channel is filled with pitch which remains liquid due to the heat in the retort and seals off the top of the retort preventing the escape of gas. The vertical partitions 3 extending crosswise of the retorts 2 do not extend the full length of the retorts. At the top these partitions are cut off about 12 inches below the tops of the retorts 2. This provides a gas space in the top of the retort. At the bottom these partitions 3 are cut off to accommodate the swinging bottom 12. The gas outlet connections 5 are provided in the retort near the upper end and above the fuel level which is maintained at the top of the partitions 3. Preferably a gas offtake connection 5 is provided on each side of the retort.

A bottom cover plate 7 provided with a channel 9 which is also filled with pitch serves to seal off the bottom of the retort and prevent the escape of gas. The bottom cover plates 7 are supported in place by means of the hooks 10.

In the lower part of the heating chamber 1, flues 17 are provided for delivering hot gas to the interior of the heating chamber. The flues 17 are provided with inlet connections 18. A flue 17 is provided on each side

of the retorts 2. These flues 17 admit either superheated steam, products of combustion or other hot gases which pass up along the sides of the retorts 2 and leave the heating chamber through the flues 15, which are also located in the top of the heating chamber, one on each side of each retort 2. The flues 15 and 17 are preferably perforated so as to uniformly distribute the heating medium.

10 The cover plates 6 are provided with lifting rings 11.

The operation of the apparatus is as follows: The cover plates are removed and the swinging bottom 12 raised into the position shown on the drawings and held in place by the dogs 14. Fuel is then charged into the compartments 4 up to the top of the partitions 3. The cover plates 6 and 7 are then placed in position and a hot gas passed through the flues 17, up through the heating chamber 1 and out through the flues 15. After the fuel is coked the cover plates are removed, the bottom 12 dropped and the fuel slides out. The retorts are then again charged and the operation repeated.

From the foregoing description it will be seen that simple and efficient means are herein provided for the rapid devolatilizing of a fuel. The thick partitions 3 extending crosswise of the retort rapidly conduct the heat into the mass of fuel. A plurality of compartments covered by a single cover plate, top and bottom, insures a minimum of labor in the operation. While the elements shown and described are well adapted to serve the purpose for which they are intended it is to be understood that the invention is not limited to the precise construction set forth.

40 40 What I claim is:

1. In coking apparatus of the type described a heating chamber, a retort extending through the said heating chamber and a plurality of parallel partitions vertically disposed within the said retort.

45 50 55 2. In apparatus of the type described, a heating chamber, a vertical retort extending through the said heating chamber, a plurality of vertical partitions extending crosswise of the said retort and means for discharging a heating medium within the said heating chamber and adjacent to the sides of the said vertical retort whereby the fuel contained in the said retort is heated progressively from the outer edges toward the center.

60 65 3. In apparatus of the type described a heating chamber, a vertical retort extending through the said heating chamber, the length of the said retort being greater than the breadth thereof, a plurality of metal partitions vertically disposed and extending crosswise of the said retort whereby the said retort is divided into a plurality of narrow compartments and flues for the dis-

charge of a heating medium on each side of the said retort.

4. In apparatus of the type described a heating chamber, a vertical metallic retort extending through the said heating chamber, the length of the said retort being greater than the breadth thereof, a plurality of heat conducting partitions vertically disposed and extending crosswise of the said retort and flues for the discharge of a heating medium within the said heating chamber and on each side of the said retort. 75

5. In apparatus of the type described, a heating chamber, a vertical metallic retort extending through the said heating chamber, the length of the said retort being greater than the breadth thereof, a plurality of heat conducting partitions vertically disposed and extending crosswise of the said retort, a gas tight cover for the top of the 80 said retort, the said cover adapted to being removed for the charging of fuel, a removable gas tight cover for the bottom of the said retort, a gas offtake connection for the removal of the products of distillation 85 from within the said retort, and means for the discharge of a hot gas within the said heating chamber and adjacent to the sides 90 of the said metallic retort.

6. In apparatus of the type described, a 95 heating chamber, a vertical metallic retort extending through the said heating chamber, the length of the said retort being greater than the breadth thereof, a plurality of heat conducting partitions vertically disposed and extending crosswise of the said retort, a removable gas tight cover for the top of the said retort, a swinging bottom under the said partitions and within the 100 said retort adapted to support the fuel 105 within the retort and a gas tight cover closing the bottom of the retort and removably supported therefrom.

7. In apparatus of the type described, a heating chamber, a vertical cast iron retort 110 extending through the said heating chamber, the length of the said retort being greater than the breadth thereof, a plurality of parallel metal partitions vertically disposed and extending crosswise of the said 115 retort, a liquid sealed cover plate for the top of the said retort, a liquid sealed bottom plate for the bottom of the said retort and flues for the discharge of a heating medium within the said heating chamber and 120 on each side of the said vertical cast iron retort.

8. In apparatus of the type described, a heating chamber, a vertical retort extending through the said heating chamber, a plurality of metal partitions vertically disposed and extending crosswise of the said retort, a flue for the discharge of a heated gas within the said heating chamber and near 125 the bottom thereof and an offtake flue for 130

removing the heated gas discharged from the first named flue and located near the top of the said heating chamber.

9. In apparatus of the type described, a 5 heating chamber, a vertical metallic retort extending through the said heating chamber, the length of the said retort being greater than the breadth thereof, a plurality of metal partitions vertically disposed 10 and extending crosswise of the said retort, a perforated flue on each side of the said retort and parallel thereto located within the said heating chamber and near the bottom thereof, each of the said flues being adapted 15 to discharge a heated gas adjacent to the walls of the said retort and a perforated off-take flue for the removal of the said gas on each side of the said retort located within the said heating chamber and near the top 20 thereof, whereby a heated gas is caused to flow from the said bottom flues upward and adjacent the sides of the said retort and out through the said off-take flues.

10. In apparatus of the type described, a 25 heating chamber, a vertical metallic retort extending through the said heating chamber, the length of the said retort being greater than the breadth thereof, a plurality of partitions vertically disposed and extending crosswise of the said retort, the said partitions being tapered from bottom to top and the side walls of the said retort being spaced a greater distance apart at the bottom than at the top whereby a plurality of 30 tapering compartments are formed within the said retort, the large end of the said compartments being located at the bottom of the said retort.

11. In apparatus of the type described, a 40 heating chamber, a plurality of vertical cast iron retorts, of rectangular horizontal section extending lengthwise of the said chamber, each retort being divided by partitions into a plurality of narrow vertical compartments, a gas tight removable cover forming the top of each of the said retorts, a gas tight 45 removable cover forming the bottom of each of the said retorts, a gas off-take pipe for the removal of the products of distillation

from each of the said retorts and means for 50 supplying a heating medium within the said heating chamber and on each side of the said cast iron vertical retorts.

12. In apparatus of the type described, a plurality of parallel vertical metallic retorts, a heating chamber inclosing the said retorts, a flue for the discharge of hot gas 55 between each of the said retorts and near the bottom of the said heating chamber and a gas off-take flue between each of the said 60 retorts and near the top of the said heating chamber, whereby a heated gas is caused to flow from the bottom to the top of the said heating chamber and between the said retorts therein.

13. In apparatus of the type described, a 65 vertical open ended retort, a plurality of vertical open ended compartments within the said retort and a plurality of gas tight covers for each end of the said retort, each 70 of the said covers being common to a plurality of the said compartments.

14. In apparatus of the type described a 75 vertical open ended retort of rectangular section, a plurality of narrow open ended vertical compartments within the said retort and liquid sealed gas tight covers closing the top and bottom ends of the said retort common to a plurality of the said compartments.

15. In apparatus of the type described, a 80 vertical metallic retort, a plurality of vertical compartments within the said retort, a space beneath the said compartments and within the said retort, a swinging bottom 85 within the said space and common to all of the said compartments for the support of fuel therein, and gas tight covers for the top and bottom of the said retort, substantially as described.

In testimony whereof I have signed my name to this specification in the presence of two subscribing witnesses.

CLAUDE M. GARLAND.
